UNITED STATES PATENT OFFICE.

CARL WINKLER, OF BERNE, SWITZERLAND.

PRINTING-MACHINE HAVING A CONTINUOUSLY-ROTATING CYLINDER.

1,241,321.

Specification of Letters Patent. Patented Sept. 25, 1917.

Application filed October 7, 1915. Serial No. 54,543.

To all whom it may concern:

Be it known that I, CARL WINKLER, a citizen of the Swiss Republic, residing at Berne, in the Swiss Republic, have invented

5 new and useful Improvements in Printing-Machines Having Continuously-Rotating Cylinders, of which the following is a specification.

10 My present invention relates to a printing machine having a continuously rotating printing or sheet carrying cylinder. According to my invention a press of this kind is so improved that the attendance and accessibility is much facilitated and 15 the external dimensions are reduced to a minimum. Further, means are provided to obtain an accurate register in placing the sheets into the machine and to admit of the sheets being delivered from the printing 20 cylinder with the freshly printed surface upward.

In the drawing a printing machine constructed according to my invention is shown by way of example,

25 Figure 1 being a side elevation of same, Fig. 2, a section through the printing cylinder and sheet feeding device on a larger scale;

30 Fig. 3 is a front view of the printing cylinder and sheet feeding device together with the mechanism for driving said parts.

The sheet feeding device *a* takes the sheets from the feed table *b* arranged over the delivery table *c* and leads them by its periodic 35 motion to the printing cylinder *d*. Underneath this printing cylinder *d* reciprocates the form carriage *e*, which is moved in known manner by a rotating spur-wheel *f* engaging first one and then the other of 40 two toothed racks *g*, *h*, which, as will be seen from Fig. 2, are provided on the form carriage *e*. In order to bring the spur-wheel *f* alternately in engagement with said racks *g* and *h*, it can be moved in the direction of 45 its axis, or be raised and lowered in its own plane of rotation according to the construction chosen. Before the change in the direction of motion of the carriage *e* takes place a roll *i* carried by the crank *k* mounted

50 on the shaft of the spur wheel *f* enters a slot *l*, provided at each end of the carriage *e* and simultaneously the spur-wheel *f* is moved out of engagement with the toothed rack with which it was in engagement during the 55 stroke being completed. The roll *i* then moves the carriage slowly until the change of

motion has taken place and then more quickly until the spur-wheel *f* has been brought into engagement with the other rack, whereupon said roll leaves the slot. 60

Of essential importance in this printing machine is the fact that the sheets are not fed immediately from the feed table *b* to the printing cylinder *d*, but are taken from the table *b* by the feed device *a* and then 65 forwarded by this device *a* to the printing cylinder *d*. The provision of the feed device *a* is rendered necessary by the fact that the printing cylinder is rotated in the opposite direction to that of existing printing 70 machines, that is, it rotates toward the feed table, as seen from above. This direction of rotation of the printing cylinder is necessary in order to cause the sheets to be delivered from the printing cylinder to the 75 delivery table underneath the feed table with the freshly printed surface upward. By this arrangement the access to the machine and its attendance, as above mentioned, are much facilitated and the outside 80 dimensions of the machine and the arrangement of the various mechanisms are much better than in existing machines, so that an economy of time and space is effected.

One construction of the feed device *a* is 85 described below by way of example with reference to Figs. 2 and 3, in which construction a cylinder is used for the purpose.

The printing cylinder *d* is driven from the driving shaft by the spur-wheels *m*, *n*, *o*. 90 To the printing cylinder *d* is fastened a toothed segment *p*, which drives the spur-wheel *q* secured to the cylinder *a*. As soon as the end *p'* leaves the spur-wheel *q* the cylinder *a* is arrested by the fork *r*. This fork 95 *r* is turned about the pin *r'* and is moved by the eccentric *s*² (Fig. 1) by means of the rod *s*³. When the opposite end of the toothed segment *p* again reaches the spur-wheel *q* and the fork *r* is lowered the cylinder *a* is turned again. 100

On both the cylinder *a* and printing cylinder *d* gripper mechanism of any suitable kind is provided. The sheets to be printed are placed on the feed table *b* against the 105 stops *t* and are taken hold of by the gripper mechanism *t'* of the feed device *a*, which can be uniformly done. As the feed device at the time is stationary an exact register is possible. The sheet taken hold of by the 110 gripper mechanism is wound on the cylinder *a* by the next rotation of said cylinder and

the front edge of the sheet is caught by the gripper mechanism t^2 on the printing cylinder d , so that said sheet is wound around the cylinder d and led over the form on the reciprocating carriage e . During this rotation of the cylinder d the tongues u are raised, but before the front edge of the printed sheet again reaches said tongues they are lowered toward the surface of said cylinder and the sheet is thus diverted on the conveying device v by which it is conveyed to the table c .

Fig. 1 shows a device for placing a print protecting sheet on each sheet placed on the table c . This device consists of the endless belts w and x , which pass over the rolls w' , w^2 , w^3 , w^4 , w^5 , w^6 and x' , w^3 , x^2 , x^3 , x^4 respectively. The protective sheet is placed between the rolls w' and w^2 , being guided by the plate y and said sheet is then conveyed by the belts w , x and delivered between the rolls w^4 and x^2 to the table c .

What I claim and desire to secure by Letters Patent of the United States is:—

25 1. A printing machine, comprising a feed table, a delivery table below the feed table, a feed-device for feeding the sheets from the feed-table, a continuously rotating impression cylinder, said cylinder rotating in the direction of the feed and delivery tables, a reciprocating form-carriage below the cylinder, and conveying means conveying the sheets from the cylinder to the delivery table, substantially as set forth.

35 2. In a printing machine, a feed table, a feed-cylinder, a continuously rotating impression cylinder, means for intermittently operating the feed cylinder from the impression cylinder, a reciprocating form carriage below the impression cylinder, a delivery table below the feed table, a conveying device leading from said impression cylinder to the delivery table, and means to

40 divert the front edge of the printed sheets from said continuously rotating cylinder, 45 said means in one position permitting the sheet on the cylinder to be carried along by said cylinder and when moved into another position serving to direct the sheet on to said conveying device.

50 3. A printing machine, comprising a feed table, a delivery table below the feed table, a feed device for feeding the sheets from the feed table, a continuously rotating impression cylinder, said cylinder rotating in the direction of the feed and delivery tables, a reciprocating form carriage below the cylinder, conveying means conveying the sheets from the cylinder to the delivery table, and means between the feed and delivery tables 55 for placing a protecting sheet on each sheet placed on the delivery table.

4. In a printing machine, a feed table, a feed cylinder, a continuously rotating impression cylinder, means for intermittently operating the feed cylinder from the impression cylinder, a reciprocating form carriage below the impression cylinder, a delivery table below the feed table, a conveying device leading from the impression cylinder to the delivery table, and pivoted tongues adapted to be moved toward and from the impression cylinder, said tongues when moved away from the cylinder permitting the sheet on the cylinder to be carried along by said cylinder and when moved toward the cylinder serving to direct the sheets on to said conveying device.

75 In testimony whereof I have signed my name to this specification in the presence of 80 two subscribing witnesses.

CARL WINKLER.
